UNITED STATES PATENT OFFICE.

JAMES GRIMES, OF WICHITA, KANSAS.

DESIGN FOR A CLOTHES-PIN.

46,852.

Specification for Design.

Patented Jan. 12, 1915.

Application filed September 18, 1914. Serial No. 862,417. Term of patent 3½ years.

To all whom it may concern:

Be it known that I, JAMES GRIMES, a citizen of the United States, residing at Wichita, in the county of Sedgwick and State of Kansas, have invented a new, original, and ornamental Design for Clothes-Pins, of which the following is a specification, reference being had to the accompanying drawing, forming a part thereof.

The figure is a perspective view of a clothes pin, showing my new design.

I claim:

The ornamental design for a clothes pin, as shown.

JAMES GRIMES.

Witnesses:

A. W. WILSON,
ORIN M. BAKER.
